(57) **CLAIM**

The ornamental design for a rocking chair, as shown and described.

DESCRIPTION

FIG. 1 is a front, right perspective view of a rocking chair showing my new design;
FIG. 2 is a front perspective view thereof;
FIG. 3 is a rear perspective view thereof;
FIG. 4 is a right side perspective view thereof, the left side perspective view being a mirror image;
FIG. 5 is a top perspective view thereof;
FIG. 6 is a bottom perspective view thereof; and,
FIG. 7 is an additional front, right perspective view illustrating the design of FIGS. 1-6 in a stacked configuration.
The broken lines illustrate environmental structure and form no part of the claimed design.
The drawings include surface shading that represents contour and not surface ornamentation.
